UNITED STATES PATENT OFFICE.

JASPER G. EDWARDS AND HAROLD T. HOLDING, OF CEMENT, OKLAHOMA.

ADJUSTABLE BRACE.

Application filed December 5, 1927. Serial No. 237,848.

This invention relates to an adjustable brace designed primarily for use in connection with cable tools and rotary drilling rigs, but it is to be understood that an adjustable brace in accordance with this invention may be employed for any purposes for which it is found applicable, and the invention has for its object to provide, a strong, durable, compact, adjustable and conveniently applied brace for bracing and for coupling and bracing a pair of elements together in a thoroughly efficient manner.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is an elevation of an adjustable brace in accordance with this invention.

Figure 2 is a fragmentary view, in end elevation, upon an enlarged scale and looking at right angles to the showing in Figure 1.

Figure 3 is a section on line 3—3 Figure 1 upon an enlarged scale.

Figure 4 is a section on line 4—4 Figure 35 1 upon an enlarged scale.

Figure 5 is a section on line 5—5 Figure 3.

Figure 6 is a perspective view of one of the abutment blocks.

An adjustable brace, in accordance with this invention, includes a pair of telescopic tubular members 1, 2 and each of which has a closed outer end as at 3 and an angle shaped extension projecting from the outer end 3 and disposed at an angle with respect thereto. The extension at the outer end of the section 1 is indicated generally at 4 and the extension at the outer end of the section 2 is indicated generally at 5. The extensions 4, 5 are oppositely disposed with respect to each other and each consists of a pair of arms 6, 7, the latter being of less length than the former and projects inwardly from the outer end thereof at an inclination. The arm 6 is formed with apertures 8 for the passage of holdfast devices to fixedly secure

an extension to the element with which it is associated when bracing and coupling together a pair of elements.

The section 2 extends into the section 1 and in proximity to its inner end is provided with a pair of lengthwise extending, diametrically opposed slots 9, 10 of appropriate length. The section 1 at its inner end is provided with a pair of lengthwise extending, diametrically opposed slots 11, 12 of appropriate length.

The sections 1 and 2 are adjusted relatively to each other and secured in adjusted position by a pair of oppositely disposed abutment blocks 13, 14, a pair of oppositely disposed wedges 15, 16 and a pair of clamping devices generally indicated at 17.

Each abutment block comprises a rectangular body portion 19 formed with a pair of spaced transverse grooves 20, 21 and laterally flanged at one end as at 22. The blocks 13 and 14 are adapted to extend through the slots 9, 10, 11 and 12 and are oppositely disposed with respect to each other. When the blocks are employed, the grooves of one block have positioned therein the outer end walls of the slots 9, 10 and the other of said blocks is seated on the outer end walls of the slots 11, 12. See Figure 3. When the blocks 13 and 14 are mounted in position, they are arranged in spaced relation, and the wedges 15 and 16 extend between the blocks. As the blocks are oppositely disposed, when mounted in position, the flanges 22 of the blocks overlap the section 1 at opposite sides thereof. See Figure 3.

Each wedge comprises a triangular body portion 23 having the larger end thereof formed integral with a rectangular plate 24 of greater width than the thickness of the body portion 23 and of greater length than the width of the latter and said plate 24 is disposed relative to the body portion 23 whereby it will extend from each side edge thereof, but one of the extending parts of said plate is of greater width than the other and bifurcated as at 25. The smaller end of the body portion 23 terminates in an inclined threaded projection 26 having the opposite sides thereof flattened as at 27 for passage through the bifurcated part of the plate 24. Figure 3.

Each securing device comprises a nut 28 and a washer 29. The washers 29 are inter-

posed between the nuts 28 and the plates 24 of the wedges 15, 16 when the wedges are arranged in position. Figure 3. The wedges 15 and 16 are oppositely disposed relatively 5 to each other and the inclined side of one wedge slides against the inclined side of the other wedge. The projection or extension 10 26 of the wedge 15 extends through the plate 24 of the wedge 16 and the extension or projection 26 of the wedge 16 extends through the bifurcated portion of the plate 24 of the wedge 15. When the wedges 15 and 16 are arranged in position, the straight side of the wedge 15 is positioned against the block 15 13 and the straight side of the wedge 16 is positioned against the block 14. Figure 3. The wedges 15 and 16, in connection with the blocks 13, 14 provide means for shifting the sections 1 and 2 of the body portion 20 of the brace, relatively to each other, and after said sections have been shifted to the desired extent, the securing devices 17 are mounted in position and said sections 1 and 2 are fixedly retained in their adjusted 25 position. Owing to the manner of setting up the blocks 13, 14 relative to the wedges 15, 16 and the providing of these latter with removable securing devices, the sections 1, 2 can be released from bracing position, 30 with respect to a pair of elements, when desired.

It is thought the many advantages of an adjustable brace, in accordance with this invention, can be readily understood, and 35 although the preferred embodiment of the invention is as illustrated and described, yet it is to be understood that changes in the details of construction can be had which will fall within the scope of the invention 40 as claimed.

What we claim is:

1. An adjustable brace comprising a body portion formed of a pair of telescopic sections, each of said sections formed with a 45 pair of diametrically opposed slots, the slots of one section registering with the slots of the other section, a pair of abutment blocks extending through said registering slots, a pair of oppositely disposed wedges interposed between said blocks, said wedges in-

cluding threaded projections and bifurcated plates, said projections of one wedge extending through the bifurcated plate of the other wedge, and means mounted on said projections for maintaining said wedges in 55 set position.

2. An adjustable brace comprising a body portion formed of a pair of telescopic sections, oppositely disposed abutment blocks extending through said sections diametrically thereof, oppositely disposed adjusting elements positioned between said blocks and arranged in abutting relation, one of said elements having one end thereof extending through one end of the other of said elements, and means mounted on said ends for maintaining them in set position. 60

3. An adjustable brace comprising a body portion formed with a pair of telescopic sections, a pair of oppositely disposed abutment blocks extending through said sections diametrically thereof and arranged in spaced relation, one of said blocks receiving one of said sections and the other of said blocks seated on the other of said sections, 70 and a pair of oppositely disposed, abutting adjusting elements having threaded projections at one end, the projection of one element being oppositely disposed with respect to the projection of the other of said elements, the projection of one element extending through one end of the other element, and means mounted on the said projections for detachably securing said elements in adjusted position. 75

4. An adjustable brace comprising a body portion formed with a pair of telescopic sections, abutment blocks extending diametrically of said sections and arranged in spaced relation, abutting, interengaging adjusting elements positioned between and abutting against said blocks, and means mounted on one of said elements and engaging the other of said elements for maintaining said elements in adjusted position. 80

In testimony whereof, we affix our signatures hereto.

JASPER G. EDWARDS.
HAROLD T. HOLDING.
